UNITED STATES PATENT OFFICE.

DIEDRICH OLTMANNS, OF SOUTH BEND, INDIANA.

AUTOMATIC WAGON-BRAKE.

SPECIFICATION forming part of Letters Patent No. 323,521, dated August 4, 1885.

Application filed March 10, 1885. (No model.)

To all whom it may concern:

Be it known that I, DIEDRICH OLTMANNS, of South Bend, in the county of St. Joseph and State of Indiana, have invented certain new and useful Improvements in Automatic Wag-
5 on-Brakes; and I do hereby declare that the following is a full, clear, and exact description thereof, reference being had to the accompa-
nying drawings, and to the letters of reference
10 marked thereon, which form part of this speci-
fication, in which—

Figure 1 is a plan view of my improved wagon-brake. Fig. 2 is a section taken longitudinally and vertically through the center
15 of the running-gear, showing the devices by
which the brake-bar is connected to the body
of the wagon. Fig. 3 is a perspective view of
the front hounds and tongue slotted as here-
inafter described; and Fig. 4 is a modifica-
20 tion, showing the brake-bar connected with
the reach by devices which actuate the former.

The object of the invention is to provide an
automatic wagon-brake adapted to be actuated
25 by the gravity of the load in the wagon-body
with or without the aid of the horses in back-
ing.

The invention consists in the construction
and novel arrangement of parts hereinafter
described, and pointed out in the appended
30 claims.

Referring to the accompanying drawings by
letters, A A designate the rear wheels, and A'
A' the front wheels, of a wagon, of which B is
the rear axle and B' the front axle, respect-
35 ively.

C is the bolster secured to the rear axle, and
provided at its ends with the uprights a a to
prevent lateral displacement of the rear end
40 of the wagon-body A'. On the bolster C is a
long roller, D D, having end bearings and a
central bearing in the three blocks b b b, se-
cured to the bolster. The object of the said
roller is to sustain the rear end of the wagon-
body and permit the same to move freely lon-
45 gitudinally.

C' is the bolster connected to the front axle
by the king-bolt b', which connects the reach E
thereto, as shown. The front end of the wagon-
50 body A' is secured to the front bolster, C',
and turns therewith.

E is the reach, having its front end passing
through and free to move in an opening, b'',

made centrally between the meeting surfaces
of the rear bolster and axle.

H H are the rear hounds, having their front
55 ends secured to a sheath, H', adapted to slide
upon the reach E.

B' B' are the front hounds secured to the
front axle and having their front ends secured
60 to the tongue F by the horizontal transverse
bolt f, which passes through said ends and
through a longitudinal slot, f', made in the
tongue, so that the latter has a certain amount
of longitudinal motion on the hounds.

G is the brake-bar, which crosses the reach
65 transversely and lies upon the sheath H'. The
brake-bar is adapted to slide forward and
backward on the sheath, its motion being lim-
ited by the long staple H'', which rises from
the reach and straddles both the brake-bar
70 and sheath H'. The brake-bar is prevented
from end motion by the pins h h, which rise
from its upper surface on each side of the
staple.

E' is a long loop, having its ends on each
75 side of the reach secured to the sheath H', and
passing through the vertical loop f', secured to
the rear end of the tongue. By means of the
said loops the tongue and sheath H' are flexi-
bly connected together.

The brake-bar is provided with the brake-
shoes G' G', adapted to bear against the wheels
A A. It is also provided at equal distances
80 on each side of its center with eye-plates c c,
to which the front ends of the rods d d are at-
tached.

c' c' are eye-plates similar to and situated
inward from the eye-plates c c, and serving a
purpose hereinafter explained.

The rear ends of the rods d d are pivotally
90 attached to the outer arms of levers I I, which
have their fulcrums at i i upon the hounds H
H. The inner arms of the levers I I have piv-
otally attached to them the rear ends of the
95 rods d' d', the front ends of which are pivoted
on the ends of the transverse plate J. The said
plate is attached to the bottom of the wagon-
body A', the attachment being by a central
pivot, j, to allow freedom of motion to the rods
d' d'.

Fig. 4 shows a modification in which the
rods d d are shortened, and have their front
ends pivoted on the reach by a pin, J.

i' i' and i'' i'' are holes through the levers I I,

80

100

to adjust the ends of the rods d d in different positions thereon. By means of the holes i i ' the leverage of the outer arms of the levers is shortened.

5 It is evident from the foregoing description that the front axle, front hounds, reach, and body have no longitudinal motion independent of each other, that the said parts can move together longitudinally on the rear axle and 10 hounds, the reach sliding through the sheath H' and opening b^2 , and that the brake-bar has an independent motion on the sheath longitudinally to the reach.

The operation of the invention is then as follows: In descending a hill the load in the wagon-body will cause the latter to slide over the roller D D , drawing the reach forward through the sheath H' , and advancing the plate J with reference to the levers I . The rods d will consequently draw the inner arms of said levers forward and turn the outer arms backward. The latter arms will, by means of the rods d' , draw the brake-bar backward on the sheath H' and bind the shoes G' against the wheels A . 25 The heavier the load with more force of momentum the wagon-body will be slid forward and the firmer the shoes will bind on the wheels. The staple H^2 limits both the sheath H' and the brake-bar in their motion. The tongue having a longitudinal motion on the front hounds will, when the horses back, press back the loop E' , and consequently the sheath H' on the reach, and will aid in braking, as is easily understood.

30 By connecting the eye-plates c' and the holes i^2 on the inner arms of the levers I the brake will act when ascending a hill, because the wagon-body and plate J will then slip backward, and the rods d and d' will act in the same

direction, carrying the brake bar and shoes backward.

When on level ground, the pull of the horses on the tongue will, by means of the loops f' and E' , reverse the described motion and take the brake-shoes from the wheels. The roller D D may be placed on the front bolster. The 45 loop E' is then omitted and the rods d attached to the eye-plates c' and holes i^2 , and the wagon-body attached to the rear bolster. The brake will then act on descending a hill.

Having described my invention, I claim— 50

1. In a wagon-brake, the combination of the body A^2 , axle B' , and reach E with the axle B , carrying the roller D D on its bolster, hounds H H , provided with the sheath H' , brake-bar G , provided with shoes G' G' , rods 55 d , levers I , and rods d' , connected at their front ends either to the wagon-body or to the reach, substantially as specified.

2. In a wagon-brake, the combination of the axles B B' , body A^2 , reach E , roller D D , hounds B^2 B^2 , and brake-bar G , actuated by the motion of the load of the hounds H H , provided with the sheath H' , loops E' and f' , tongue F , provided with the slot f , and bolt f^2 , substantially as specified. 65

3. The combination, in a wagon-brake, of the longitudinally-movable reach E , rear hounds, H H , and brake-bar G with the long sheath H' and pins h h , substantially as specified.

In testimony that I claim the foregoing as 70 my own I affix my signature in presence of two witnesses.

DIEDRICH OLTMANNNS.
